DESIGN FOR A STOOL

William L. Greyson, Flushing, N. Y.

Application September 7, 1946, Serial No. 133,178

Term of patent 14 years

(Cl. D15—8)

To all whom it may concern:

Be it known that I, William L. Greyson, a citizen of the United States, residing at Flushing, in the county of Queens and State of New York, have invented a new, original, and ornamental Design for a Stool, of which the following is a specification, reference being had to the accompanying drawing, forming a part thereof.

Figure 1 is a side perspective view of a stool showing my new design.

Figure 2 is a bottom plan view; and

Figure 3 is an end elevational view thereof.

This application is a continuation in part of my application No. D. 122,667, filed October 8, 1945, now abandoned.

I claim:

The ornamental design for a stool, substantially as shown.

WILLIAM L. GREYSON.
